Int. Cl. D8—06

U.S. Cl. D8—138

FIG. 1 is a perspective view taken from the left front side of a combined door handle and lock housing set embodying my design, shown mounted on a panel which is shown in phantom lines;

FIG. 2 is an enlarged foreshortened right side elevation taken as indicated by the lines and arrows 2—2 in FIG. 1;

FIG. 3 is an enlarged foreshortened front view taken as indicated by the lines and arrows 3—3 in FIG. 2;

FIG. 4 is an enlarged foreshortened rear view taken as indicated by the lines and arrows 4—4 in FIG. 2;

FIG. 5 is a greatly enlarged top view taken as indicated by the lines and arrows 5—5 in FIG. 3; and

FIG. 6 is a greatly enlarged section taken as indicated by the lines and arrows 6—6 in FIG. 3.

The panel shown in phantom lines forms no part of the design and has been included for purposes of illustrating environment only. Portions have been foreshortened on the drawings for convenience of illustration.
